Des. 217,647
Patented May 19, 1970

217,647

WRITING PEN CAP

Walter J. De Groft, Glen Ellyn, Ill., assignor to Sanford
Research Company, a corporation of Illinois

Filed June 24, 1968, Ser. No. 12,487

Term of patent 14 years

Int. Cl. D19—06

U.S. Cl. D74—17

FIG. 1

FIG. 2

FIG. 3

FIG. 4

FIG. 5

FIG. 1 is a side elevational view of a writing pen cap embodying the design of my invention;

FIG. 2 is an end elevational view taken from the left-hand side of FIG. 1;

FIG. 3 is an end elevational view taken from the right-hand side of FIG. 1;

FIG. 4 is a top plan view of the writing pen cap shown in FIG. 1 embodying the design of my invention; and

FIG. 5 is a bottom plan view thereof.

I claim:

The ornamental design for a writing pen cap, as shown.
